CLAIM

The ornamental design for a punch down tool, as shown and described.

DESCRIPTION

FIG. 1 is a perspective view of a punch down tool showing the design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an enlarged view of the circle marked with A in FIG. 4; and,

FIG. 9 is an enlarged view of the circle marked with B in FIG. 5.

The broken lines are for illustrative purposes only and form no part of the claimed design.
